BROOM AND METHOD OF MAKING SAME

Walter H. Zachry, Atlanta, Ga.

Original application July 14, 1933, Serial No. 681,188. Divided and this application August 20, 1934, Serial No. 740,696

11 Claims. (Cl. 300—21)

My invention relates to improvements in brooms and the like, and also to an improved process for making the same. It is a division of my copending application filed July 14, 1933, Ser. No. 681,188, to be patented No. 1,970,590 on August 21, 1934.

Briefly stated, the invention has for its primary object to generally improve the detachable handle fastening structure of the broom or the like, disclosed in the U. S. Patent No. 1,645,490, issued on October 11, 1927, to Charles Malcolm Keener and Walter H. Zachry; and to provide a novel method whereby the handle-receiving socket of the broomhead or the like,—and the broomhead itself may be formed in one substantially continuous operation.

The invention also resides in certain novel features of construction, combination and arrangement of parts, and in methods and modes of operation,—to be hereinafter described and claimed, reference being had to the accompanying drawing illustrating the invention in its now preferred form.

In the drawing,

25 Figure 1 is an elevational view of the socket forming device claimed in my Patent No. 1,970,590, and illustrating a socket blank thereon and the commencement of the threading operation;

30 Figure 2 shows the completion of the step of forming the threaded socket;

Figure 3 shows the completed broomhead, and portion of socket-forming device removed;

Figure 4 shows the novel handle and broomhead assembled, and

Figure 5 is an enlarged fragmentary section of the threaded part of the handle showing a part of the socket threads in dotted lines.

Referring to the drawing by reference characters, 16 is a spindle claimed in my Patent No. 1,970,590, and which is adapted to be inserted into and driven by the chuck of a broom winding machine which carries a spool of wire,—all as shown and described in my said patent.

45 Spindle 16 has the major portion of its tapered forward end 16c provided with raised threads 16a. Spindle 16 is provided with a plurality of circumferentially spaced radial slots 16b extending inwardly from its tapered end and into the unthreaded portion as indicated in Figures 1 and 2. A rod 17 extends through a bore of spindle 16 and has an end enlargement 17b providing a cam 17a adapted to extend into the spindle 50 bore when the rod is pulled to right (Fig. 2) for

spreading outwardly the segments of tapered spindle end 16c.

A headed stud 19a (Figs. 1, 2 and 3) carried by a cam plate or latch element 19 (Fig. 3) is adapted to be projected transversely beyond the 5 surface of the spindle 16 when the cam rod 17, 17b is pulled inwardly to spread the segments of end 16c; and such stud 19a, when so projected, is adapted to receive the loop 12a of the winding wire 12. When rod 17 is pushed outwardly (to 10 left, Fig. 3) the stud 19a disappears in spindle 16. This is all described in full detail in my Patent No. 1,970,590.

In carrying out the process or method of manufacture of a handle-receiving socket in accordance with my invention, I utilize a thin metal blank 30 in which a hole is punched adjacent one corner. Cam 17a is disposed in operative position and rod 17 actuates stud 19a outwardly as explained in my said patent. The 15 blank 30 is preferably drawn by hand about the threaded and tapered portion of spindle 16. When this has been done, the spindle 16 will be rotated. This causes the threads 16a on the spindle 16 to cause the tensioned wire 12 to compress the stock of the soft metal socket blank 30 20 between the spindle threads 16a so as to progressively form threads 31 in socket 30.

When the threading of the socket has been completed, the wire 12 will be given two or three 30 additional turns about the completed socket 30 so as to hold the convolutions of wire 12 in place between socket threads 31. See 12b in Fig. 2. Preferably such convolutions 12b go over a bent back tongue 30x of socket 30.

35 After the threading of socket 30 has been completed, the inner stiff layer 32 of broom corn will be applied to the socket portion 30 which still remains on the spindle. This broom corn layer 32 is wound onto the lower portion of the socket 40 30 as indicated at 12c. Next the outer or finer layer 33 of broom corn is applied over the coarse broom corn layer 32 to extend over the upper part of the socket 30, whereupon the winding of layer 33 upon the socket takes place as indicated at 12d 45 in Figure 3. The final phase of the winding operation is the carrying of the wire 12 upwardly from the turns 12d and winding it as at 12c about the upper end of the layer of fine broom corn 33 to provide the crown or head 33a (see Fig. 3) adjacent the upper end of the socket 30. The end 50 of the wire is secured to nail 34 in crown 33a.

Particular attention is directed to the novel automatic formation of the flange 30b at the upper end of the socket 30. This flange 55

serves to overlie and hold the upper end of the broomhead or crown 33a and is formed by the windings 12e of the wire 12 upon the stock of socket 30 at the site of the circumferential shoulder 16d, which is provided by the cylindrical rear end of spindle 16 at the junction between the same, and the tapered spindle portion 16c rearwardly of the threads 16a. The stock of socket 30 will initially slightly overlie the shoulder 16c of spindle 16 as indicated in Figures 1 and 2.

The broom handle 40 is diametrically reduced at its lower end portion which provides the helical groove 41 to receive convolutions of heavy wire to provide threads for securing the handle 40 to socket 30, as indicated at 42, 42b and 42d in Figures 4 and 5. The respective ends of this piece of heavy wire are anchored in the lower handle portion 42a as indicated at 42a and 42c, respectively.

Particular note should be taken of the fact that the first three and last three heavy wire convolutions of threads 42b and 42d, respectively, on the handle are set outwardly of the intermediate convolutions 42 so as to assure good binding action at each end of the socket 30. The handle threads 42b are preferably disposed upon a diametrically reduced cylindrical surface above the tapered portion of handle end 40a. The upper threads 42b also, after a fashion, provide a stop or abutment for the socket when the handle is screwed thereinto. In this way there is a wedging action that takes place and makes for a tight fit of handle into the socket. In other words, a fit is thus obtained which will effectively resist inadvertent relative turning of the handle with respect to the socket 30 when the broom or implement is in use. After the broomhead has been wound onto socket 30, rod 17 is moved leftwardly to release cam 17a from 16a and the stud 19a is projected inwardly into the spindle by such outward movement of rod 17 or otherwise. Then socket 30 with the broomhead thereon is removed from spindle 16 and handle portion 40a is screwed into socket 30.

Regarding handle 40, particular emphasis is laid upon the wire-provided threads 42a and 42d at the inner and outer ends of the socket-receiving handle portion 40a. Threads 42b are substantially in plane with one another and are disposed outwardly of the plane of the threads 42d which are also raised and substantially in plane with each other. This arrangement, aside from helical groove 41 and the fact that 40a may be tapered, gives the intermediate wire-defined threads 42 a taper to cause them to conform to threads 31 in the tapered socket 30. The helical groove 41 in 42 can be dispensed with if desired. When the handle thread wire 42, 42a, etc., is applied, convolutions 42 will be wound tightly into groove 41 as suggested in full lines in Figure 5. Afterwards, however, these intermediate convolutions 42 (because of their remoteness to anchor points 42a, 42c) tend to spring out as per dotted lines to engage socket threads 31.

By winding the turns of wire 12b over the bent back tongue 30x of socket 30 the subjacent turns of wire 12 are positively locked in place and the socket 30 cannot screw out of the wire turns or threads 12 when the socket 30 is removed from spindle 16 or when a handle 40 is removed after having been very tightly screwed into socket 30. The use of this tongue 30x while very desirable is not absolutely essential. Turns 12b are quite effective without tongue 30x.

Having thus described my invention, what I claim as new is:

1. In a separable head and handle structure for brooms, mops and the like, a lineally split socket of soft flexible metal and tapering to reduced diameter at one end, a length of wire having a portion helically wound about said socket to provide and maintain threads in said socket, work-engaging material disposed about said socket and aforementioned wire portion and secured thereto by windings of the remainder of said wire whereby to provide a head about said socket, a handle having a threaded end adapted to be screwed into said socket, the threads at the ends of said threaded handle portion being relatively raised as compared with adjacent threads whereby to assure of an especially tight fit with the interengaging socket threads so as to firmly connect the handle and socket, said socket thread-providing and head-forming portions of said wire cooperating with one another in tending to maintain said split socket from spreading from internal pressure of the handle.

2. In a separable head and handle structure for brooms, mops and the like, a lineally split socket of soft flexible metal, a length of wire having a portion helically wound directly against and about said socket whereby to prevent it from spreading and providing threads in said socket, and work-engaging material disposed about said socket and secured thereto by windings of the remainder of said wire whereby to provide a head about said socket and first-mentioned length of wire.

3. In a separable head and handle structure for brooms, mops and the like, including a head providing a tapered interiorly threaded socket, a socket receivable handle portion diametrically enlarged adjacent its ends as compared to the intermediate portion, the diameter of the enlargement adjacent the socket-entering end being smaller than the diameter of the rear end enlargement, a length of heavy wire wound upon said handle portion to provide threads substantially conforming to and adapted to engage the socket threads, and said handle-thread-providing wire being wound tighter upon said end enlargements than upon the intermediate handle portion whereby the latter will tend to conform to the taper of said socket.

4. The method of making a threaded socket-providing broom head or the like which comprises supporting a split soft metal socket on a spirally grooved support, progressively winding wire upon said socket from one end toward the other to compress the socket stock into said grooves, whereby to produce threads in the socket, then applying broom corn to said socket and winding the wire progressively about the broom corn in the direction of the first-mentioned end of the socket to provide a snug head about the socket, and then anchoring the wire to the head.

5. The method of making a threaded socket-providing broom head or the like which comprises supporting a split soft metal socket on a spirally grooved support, progressively winding wire upon said socket from one end toward the other to compress the socket stock into said grooves, whereby to produce threads in the socket, turning the wire several times about the socket at the end of the threads so formed therein, then applying broom corn in the direction of the first-mentioned end of the socket to provide a snug head about the socket, and then anchoring the wire to the head.

6. In a broom, a head, a sheet material socket forming the core of said head, a flexible strand

providing spirally wound convolutions about said socket to form and maintain threads therein, means carried by said socket and overlapping certain of said convolutions for anchoring said convolutions of said strand to said socket, and means including said head for securing the free ends of said strand.

7. In a broom head, a flexible sheet material socket, a strand progressively wound about said socket from one end and providing convolutions forming internal threads in said socket, the other end of said socket having a bent back tongue overlying said convolutions, and said strand having a return portion wound about said tongue to press it against said convolutions and socket whereby to anchor said convolutions to the socket.

8. In a broom head, a flexible sheet material socket, a strand progressively wound about said socket from one end and providing convolutions forming internal threads in said socket, the other end of said socket having a bent back tongue overlying said convolutions, said strand having a return portion wound about said tongue to press it against said convolutions and socket whereby to anchor said convolutions to the socket, and courses of broom material disposed about said socket and secured thereabout by said strand.

9. The method of making a threaded socket-providing broom head or the like which comprises supporting a split soft metal socket on a spirally grooved support, progressively winding wire upon said socket from one end towards the other to compress the socket stock into said grooves, whereby to produce threads in the sock-

et, then applying broom corn to said socket slightly short of one end thereof and winding the wire progressively about the broom corn in the direction of the exposed end of socket to provide a snug head about the socket, then winding the remainder of the wire about the projecting exposed end of the socket, whereby to provide a flange, and finally anchoring the terminal of said wire to said head.

10. In a separable head and handle structure for brooms, mops and the like, including a head providing an interiorly threaded socket, a socket-engageable handle portion diametrically enlarged adjacent its ends as compared to the intermediate portion, a length of heavy wire wound about the socket-engaging portion of the handle to provide thread substantially conforming to and adapted to engage the socket threads, and said handle thread-providing wire being wound in tight contact with said end enlargements only whereby the intermediate portion of the thread-providing wire of said handle will tend to lie away from the intermediate handle portion and provide a shiftable thread to conform to the socket threads even if the socket is distorted.

11. A handle for a socket head broom providing a socket engaging end portion, such end portion having spaced enlargements, and thread-providing wire wound about said socket engaging end portion into tight contact with said enlargements whereby to provide a relatively yielding intermediate wire-provided thread portion for socket engagement.

WALTER H. ZACHRY.
